UNITED STATES PATENT OFFICE.

PETER JOHN KURSCHEIDT AND HARRY E. NORWOOD, OF NEW YORK, N. Y., ASSIGNEES,
BY MESNE ASSIGNMENTS, TO PERFECT WINDOW REGULATOR CORPORATION, OF
LONG ISLAND CITY, NEW YORK, A CORPORATION OF DELAWARE.

WINDOW REGULATOR.

Application filed April 29, 1922. Serial No. 557,470.

Our invention relates to window regulators adapted to raise or lower a window upon rotation in the proper direction of a rotatable crank or handle which is mounted 5 on the device and operatively connected with the operating mechanism.

Although it is not to be so limited in its application, the invention is peculiarly applicable to that class of window regulators 10 used on vehicles, such as automobiles, and employing two sprockets or wheels, a chain or other linear member running thereover, a connection between the chain and the window and a crank for rotating one of said 15 sprockets whereby the window is raised or lowered as desired.

The principal object of the invention is the production of a window regulator of 20 simplicity of construction and of ease of operation, the invention consisting in the novel parts and combinations thereof hereinafter more particularly described and then specified in the claims:

In the accompanying drawing illustrating 25 a practical embodiment of the invention:

Fig. 1 is a front elevation of the window regulator.

Fig. 2 is a front elevation of one of the 30 slidable plates employed on the lower construction of the device.

Fig. 3 is a horizontal section on the line 3-3 of Fig. 2.

Fig. 4 is a section taken through the lower portion of the device.

Fig. 5 is a front elevation of the upper portion of the device on the line 5-5 of 35 Fig. 3.

Fig. 6 is a section taken through the upper portion of the device.

Fig. 7 is a side elevation of the crank shaft.

Fig. 8 is an end view thereof.

Fig. 9 is a front elevation of the clutch driving member.

Fig. 10 is a front elevation of the driven member.

Referring in detail to the several figures of the drawing:

Numeral 1 indicates a window which is 50 adapted to be reciprocated vertically in a suitable frame, the lower part of which is indicated at 2. Numeral 3 indicates a plate which is mounted on and secured to the lower part 2 in any desirable manner while

4 indicates a cover plate which is screwed 55 to said plate by suitable screws 5 and which forms with said plate 3 a housing containing a clutch and other mechanism to be presently described. A vertical depending bar or strap 6 is fastened at its upper end 60 to the plate 3 and at its lower end to a cross-bar 7 which is detachably secured to the side walls of other parts of the window well.

The bar 6 is provided adjacent its lower end with two slots 8 and 9 respectively, the slot 8 being so cut in the material as to form an arm 10. 11 and 12 indicate vertically slidable plates each of which is provided with depressions 13 pressed inwardly from 70 the metal and acting as anti-friction members slidably engaging the bar or strap 6. The upper ends of said plates 11 and 12 are bent inwardly into engagement with each other and within the slot 8 to form a shoulder 14. A compression spring 15 encircles the arm 10 and the upper inwardly bent ends of the plates and bears against the shoulder 14 and acts to press or force said plates downwardly on the bar or strap 6. 80

A bolt 16 extends through the slot 9 in the bar 6 and also through suitable annular openings in the plates 11 and 12. Said bolt is provided with ears or shoulders 17 engaging in slots 18 in plate 12 which slots 85 communicate with the bolt-receiving opening in said plate. The engagement of said ears with said slots acts to prevent rotation of said bolt. The hub portion 19 of a lower rotatable sprocket 20 is mounted on the enlarged annular portion 21 of the bolt 16, a longitudinal movement of said sprocket on said portion 21 being prevented by a flange 22 on said bolt and by an annular ridge 23 on the plate 12 which is pressed outwardly from the metal and which engages the side of the hub portion 19. A nut 24 is screwed on the end of the bolt and holds the plates together as is manifest, a washer 25 preferably being interposed between said nut and plate 11 and seating on a shoulder 26 formed by a depression with which said plate is provided.

An endless driving chain 27 passes over an upper sprocket 28, which is mounted on the plate 3 in a manner to be presently described, said chain being held taut by the action of the spring 15 which, as has been described, 105

presses downwardly against the vertically 70
slidable plates 11 and 12 carrying the lower
sprocket 20, thus preventing the chain from
running off said sprockets. The chain 27 is
5 connected to the window 1 by means of a
roller stud 29 engaging in a slot of a plate
30 which is secured to and depends from the
lower side of the window. A handle 31 is
10 mounted on a housing and connected with
mechanism within said housing formed by
the cover plate 4 and plate 3 whereby ro-
tation of said handle will rotate the upper
sprocket 28, thereby causing the chain 27 to
15 travel around the upper and lower sprockets
thus effecting a raising and lowering of the
window depending on the direction of ro-
tation given the handle.

Numeral 32 indicates a crank shaft which
is provided with enlarged and reduced hub
20 portions 33 and 34 rotatably received by an
annular neck 35 pressed out from the plate 4
and a removable bearing 36 respectively
which bearing is received and held within
an opening in the plate 3. (See Fig. 6.)
25 The handle or crank 31 is secured to the end
of said shaft in any desirable manner. The
shaft is provided with a substantially rect-
angular-shaped driving-member actuator 37
preferably integral therewith and having flat
30 sides and rounded ends and also end flanges
38 slidably fitting intermediate the plate 4
and a fixed clutch member 39. The flanges
38 act to prevent rocking or displacement of
a clutch driving member 42 to be presently
35 described.

The fixed clutch member 39 is provided
with pins 40 extending through depressions
in the plate 4 the ends of said pins being riv-
eted over on said plate within said depre-
40 sions, whereby the clutch member is securely
held against movement. Said clutch mem-
ber is also provided with an enlarged open-
ing 41 extending therethrough having a ser-
rated or toothed edge as indicated.

45 The driving member of the clutch is in-
dicated at 42 and is provided with outwardly
projecting pins 43 and an opening 44 having
an upper flat wall, rounded side walls and
a lower wall having an irregular or cam sur-
50 face. (See Fig. 9.) The lower portion of
the driving member is also provided with
teeth 45 adapted to interfit with the teeth of
the opening 41 of the fixed member 39. The
opening 44 is adapted to receive the actuator
55 37 on the shaft 32 and the opening 41 of the
fixed clutch member 39 receives the driving
member 42, the fixed clutch member and
driving member 42 both lying in the same
plane. When the handle or crank on the
60 shaft 32 is not rotated or operated one of the
flat sides of the actuator 37 engages the up-
per flat wall of the opening 44 while its
curved ends engage the rounded side walls of
said opening as shown in Fig. 5.

65 Numeral 46 indicates the driven member

loosely carried on the shaft and which com-
prises a flat disk provided with slots 47
therein slidably receiving the pins 43 of the
driving member 42. One of said slots car-
ries a spring 48 bearing against one of the
pins 43 and acts to retain the driving mem-
ber 42 in the position shown in Fig. 5 with
70 its teeth 45 lockingly engaging the teeth of
the fixed member 39, whereby rotation of the
shaft 32 will be prevented if rotation is at-
tempted from the end adjacent the hub por-
tion 34 as is obvious.

The driven member 46 is provided with
outwardly projecting pins 49 entering and
interfitting with suitable openings in a pin-
80 ion 50 loosely mounted on the shaft, said
pinion meshing with a large gear 51. When
the crank or handle is rotated the part 37 of
the shaft takes the position shown in Fig. 9
85 or at right angles to said position depending
on the direction of rotation of the crank or
handle. As the part 37 may not completely
rotate within the opening 44 it forces the
driving member against the action of the
90 spring 48 to move in a direction whereby the
teeth 45 will become disengaged from the
teeth of the fixed member 39, after which the
member 42 will rotate with the shaft. Ro-
tation of the shaft thus effects a rotation of
95 the driven member 46 due to the pins 43 en-
gaging in the slots 47. When the driven
member rotates the pinion 50 and large gear
51 likewise rotate because of the connection
between these parts as hereinbefore de-
scribed. When the crank or handle is re-
100 leased the parts automatically lock as the
spring 48 bearing against one of the pins 43
acts to move the driving member 42 into its
first position whereby its teeth 45 will en-
gage the teeth of the fixed member 39, the
105 part 37 being also forced back into normal
position shown in Fig. 5. For all practical
purposes the driven member 46 and pinion
50 may be considered one part, they being
110 constructed of two parts merely for conven-
ience of manufacture.

The gear 51 is fixed to a shaft 52 pro-
vided with a flange 53 acting as a stop to
prevent a longitudinal movement of the
gear thereon. One end of said shaft 52 is
115 hollowed out as at 54, this end of the shaft
being supported by a depressed support 55
pressed inwardly from the metal of the plate
4 and entering the hollowed out portion
54. The other end of the shaft is mounted
120 in an annular neck 56 pressed out from the
metal of the plate 3 and forming a bearing
for said shaft, a washer 57 being preferably
interposed between said bearing and shaft.
The plate 3 is also provided with an annu-
lar ridge or bead 58 pressed inwardly from
125 the plate and acting as an anti-friction sup-
port slidably engaging the side of the gear
51 and adapted to prevent rocking thereof.
The end of the shaft 52 is reduced and re-
130

ceives the sprocket 28 which is rotatable therewith and which is adapted to engage a shoulder 59 on the shaft to prevent a longitudinal movement of the sprocket thereon. 5 Numeral 60 indicates a bolt extending through the shaft and which is provided with a head 61 received by the recess 54. The opposite end of said bolt carries a washer 62 adapted to prevent removal of the 10 sprocket from the shaft.

The plate 4 is provided with an inwardly extending lug 63 cut from the metal to which one end of a counterbalancing spring 64 is secured or hooked, the other end of 15 said spring being secured or hooked to a lug 65 on the gear 51. The spring is supported and prevented from spreading outwardly by additional lugs 66 on said gear and is prevented from too great an inward 20 movement, which might tend to interfere with the rotation of the shaft 52, by a semi-circular shaped ridge or bead 67 pressed inwardly from the plate. The counterbalancing spring per se is old although in so 25 far as we are aware the particular manner of mounting and holding the same in proper position as shown and described is new. The function of the spring is to assist in the raising of the window, the spring being wound up by the lowering thereof.

What we claim as our invention is:—

1. In a window regulator, a bar, a slide comprising a plate slidable on said bar, a wheel rotatably mounted on said slide, a 35 linear member running over said wheel for transmitting motion, a spring engaging said plate and said bar for tensioning the linear member and anti-friction members pressed inwardly from the metal of said plate and 40 slidably engaging said bar.

2. In a window regulator, a support provided with upper and lower slots therein, an arm extending within said upper slot, a sprocket, a chain extending over said 45 sprocket for transmitting motion, a bolt extending through said lower slot on which said sprocket is mounted, a slide comprising two plates slidable on opposite sides of said support and carried by said bolt and 50 having their ends turned within said upper slots to form a shoulder, anti-friction members pressed inwardly from the metal of said plates and slidably engaging said support, a spring within said upper slot supported 55 by said arm and the ends of said plates and bearing against said shoulder and adapted to tension said chain, a shoulder on one of said plates, a washer seated thereon and carried by said bolt and a nut on said bolt engaging 60 said washer.

3. In a window regulator, a lower rotatable member, a housing, a shaft mounted

on said housing and extending therein and provided with a hollow end, a depression pressed inwardly from the metal of a wall 65 of said housing and entering the hollow end of said shaft for supporting the same, an upper rotatable member mounted on said shaft and a linear member extending over said rotatable members for transmitting motion. 70

4. In a window regulator, a lower rotatable member, a housing, a bearing on one wall of said housing, a shaft mounted on said bearing and extending within said housing and provided with a hollow end, a depression pressed inwardly from said housing and entering the hollow end of said shaft for supporting the same, a rotatable member mounted on the end of said shaft, a linear 80 member running over said rotatable members for transmitting motion and a bolt extending through said shaft and provided with a head received by the hollow portion of said shaft and carrying a washer on the other end 85 for retaining said upper rotatable member in position.

5. In a window regulator, a lower rotatable member, a housing, a shaft mounted on said housing and extending therein, a gear 90 mounted on said shaft within said housing, an upper rotatable member mounted on said shaft, a linear member extending over said rotatable members for transmitting motion, a counterbalancing spring secured to said 95 housing and to said gear and adapted by its action to assist in raising the window and a ridge pressed inwardly from the metal of a wall of said housing and partially surrounding said shaft in spaced relation thereto and 100 adapted to prevent engagement of the same by said spring.

6. In a window regulator, a lower rotatable member, a housing, a shaft mounted on said housing and extending therein, a gear 105 mounted on said shaft within said housing, an upper rotatable member mounted on said shaft, a linear member extending over said rotatable members for transmitting motion, a counterbalancing spring secured to said 110 housing and adapted by its action to assist in raising the window, lugs on said gear for supporting said spring, a ridge pressed inwardly from the metal of a wall of said housing and partially surrounding said 115 shaft and adapted to prevent engagement of the same by said spring and an annular bead pressed inwardly from a wall of said housing and adapted to slidably engage said gear.

Signed at New York, in the county of New York, and State of New York, this 28th day of April, A. D. 1922.

PETER JOHN KURSCHEIDT.
HARRY E. NORWOOD.
